UNITED STATES PATENT OFFICE.

MEYER G. COHEN, OF NEW YORK, N. Y.

WRAPPING AND BALING FABRIC.

1,215,777.

Specification of Letters Patent. Patented Feb. 13, 1917.

Application filed October 28, 1914, Serial No. 868,945. Renewed December 27, 1916. Serial No. 139,183.

To all whom it may concern:

Be it known that I, MEYER G. COHEN, a citizen of the United States of America, and a resident of New York, county and State 5 of New York, have invented certain new and useful Improvements in Wrapping and Baling Fabrics, of which the following is a specification, reference being had to the accompanying drawing, forming a part 10 thereof.

My invention relates to wrapping and baling fabrics and has for its object to provide an air-proof, water-proof and dust-proof fabric which is particularly adapted 15 to be used instead of burlap, and has many advantages which burlap does not possess.

Burlap has been very largely used for baling and wrapping purposes because it is strong and tough and may be sewed readily. 20 It however, has the disadvantage of being neither dust-proof nor water-proof and tremendous quantities of goods have been damaged, with heavy losses to shippers and carriers on this account. In order to protect them from dust goods have frequently 25 been wrapped first in paper and then in burlap which involves considerable expense and time.

It has been my aim to provide a wrapping fabric which shall possess the advantages and avoid the disadvantages of burlap and for convenience in identification I refer to my improved fabric as "antiburlap."

Other objects and advantages of my invention will be set forth hereinafter, and in order that my invention may be thoroughly understood, I will now proceed to describe the same in the following specification, and 40 then point out the novel features thereof in appended claim.

Referring to the drawings:

Figure 1 is a perspective view of a bale wrapped with my improved fabric and illustrating its utility.

A sectional view of the fabric itself, drawn on a large scale to bring out its construction, is shown in Fig. 2.

The bale 10 of Fig. 1 may contain cotton 50 or some other material and is closely

wrapped with antiburlap shown at 11. With reference to both Figs. 1 and 2, the antiburlap consists of a tough, flexible sheet of paper 15 having on its outer surface a coating 16 of varnish or other suitable 55 water-proof gum. Pasted to its inner surface is a sheet of relatively thin cloth 17 which is closely united with the paper.

As indicated in the drawings, the antiburlap can readily be sewed and drawn closely 60 about a bale or package and constitutes an air-proof, dust-proof and water-proof covering.

Among the advantages which distinguish my improved fabric from those hitherto 65 known, the following may be mentioned: it may be easily and neatly cut; thus a great deal of time may be saved in baling and wrapping, especially by manufacturing concerns which utilize tremendous quantities 70 of wrapping material. The complete package can be easily marked on account of its smooth surface. The fabric can be manufactured in large quantities at small cost. The fabric may be utilized for making bags 75 or sacks for coal, cement, coffee, potatoes and the like.

I am aware that cloth and paper have been united but my improved fabric differs from those hitherto known in essential features which particularly adapt it for the purpose for which it is intended and for which none of the fabrics of the prior art are adapted.

What I claim is:

A baling and wrapping fabric composed of a relatively strong, flexible paper having a coating of varnish on its outer surface to render it water-proof, and a relatively thin cloth pasted to its inner surface, whereby it 90 is water-proof and is also susceptible of being sewed and used like a coarse cloth.

In witness whereof, I have hereunto set my hand this 23rd day of October, 1914, in the presence of two subscribing witnesses. 95

MEYER G. COHEN.
